By

UNITED STATES PATENT OFFICE.

EDMUND DICKEY, OF LANCASTER, OHIO.

DESIGN FOR A DIMMING-LENS.

51,752.

Specification for Design.

Patented Feb. 12, 1918.

Application filed November 8, 1915. Serial No. 60,449. Term of patent 7 years.

To all whom it may concern:

Be it known that I, EDMUND DICKEY, a citizen of the United States, residing at Lancaster, Fairfield county, Ohio, have invented a new, original, and ornamental Design for Dimming-Lenses, of which the following is a specification, reference being had to the accompanying drawing, forming part thereof, in which—

Figure 1 is a face view of a dimming lens showing my new design, and,

Fig. 2 is an edge view of the structure shown in Fig. 1.

The design consists of a circular head-light lens including a central concavo-con-

vex surface on which is stippled a figure suggesting a sunburst or seal, said figure being surrounded by a plain circular surface forming a continuation of the concavo-convex surface and which latter being in turn encircled by a peripheral flange disposed at right angles to the axial line of the lens.

I claim:

The ornamental design for a dimming lens, as shown and described.

EDMUND DICKEY.
